GARMENT

Esther Cadous, New York, N. Y.

Application April 8, 1950, Serial No. 154,867

2 Claims. (Cl. 2-37)

2

1 This invention relates to foundation garments for women and has for its object to provide a novel and improved garment of this type which is adapted to mold the figure and provide a smooth foundation for outer garments while enhancing the comfort and freedom of movement of the wearer.

Another object of the invention is to provide a garment of the above type which will not ride up on the figure whether or not garters are worn, and which, in the case of garments employing garters, will not depend on the garters as an anchoring means and will thus protect the hose against undue strain.

Still another object is to provide a garment of the foregoing type employing stiffening busks to assist in flattening the diaphragm or abdomen of the wearer and having built-in areas of sponge rubber which not only gently grip the body to anchor the garment in place but also cushion the ends of the busks to prevent chafing and wear.

Various other objects and advantages will be apparent as the nature of the invention is more fully disclosed.

When foundation garments such as corsets, girdles, etc., are worn without garters, they tend to ride up on the body to the discomfort and annoyance of the wearer. Furthermore, in the usual case where garments of this type employ garters which tend to prevent the garment from hitching up, the garters exert a strain on the hose which frequently causes runs or tears, especially in the sheer nylon and silk hosiery in common use today.

My invention provides a foundation garment such as a corset, girdle, combination corset and brassière, pantie girdle, etc., which will not ride up on the figure whether or not garters are worn, and which affords the special advantage of protecting and preserving the hose in the case of garments employing hose supporters.

In the preferred embodiment of the invention the lower edge of the foundation garment has one or more inner strips or pads of soft sponge rubber which provide a grip against the skin of the wearer to prevent the garment from riding up on the body, and the hose supporters are preferably secured to these sponge rubber areas as by stitching. In the case of some garment, as hereinafter described, additional internal areas of sponge rubber are also provided, especially at the sides and even at the top of the garment where added gentle traction is desirable.

In the case of figure molding foundation garments employing vertical busks or stays to assist

in attaining the desired figure control, the interior areas of the garment underlying the upper ends of the busks are preferably lined with sponge rubber which not only further assists in anchoring the garment on the figure but also prevents the busks from chafing or digging into the body in whatever position the wearer may assume.

Although the novel features which are characteristic of my invention are set forth more in detail in the claims appended hereto, the nature and scope of the invention may be better understood by referring to the following description taken in connection with the accompanying drawings forming a part thereof, in which certain specific embodiments have been set forth for purposes of illustration.

In the drawings:

Fig. 1 is a front view of a model wearing a combination corset and brassière having a corset portion embodying the invention;

Fig. 2 is a rear view of a combination garment similar to that of Fig. 1 but having a different arrangement of sponge rubber inserts;

Fig. 3 is a transverse section taken on line 3-3 of Fig. 1;

Figs. 4 and 5 are broken front and rear views, respectively, of a girdle showing another embodiment of the invention;

Fig. 6 is a perspective view of a strip of sponge rubber having a backing of one-way stretch elastic fabric, as used in the garment of Figs. 4 and 5;

Fig. 7 is a front view of a girdle having vertical stiffening busks and illustrating another embodiment of the invention;

Fig. 8 is front view of a garter belt constructed in accordance with the invention;

Figs. 9 and 10 are front and rear views, respectively, of a pantie girdle embodying the invention;

Figs. 11 and 12 are front and rear views, respectively, of a girdle embodying still another construction;

Fig. 13 is a plan view of the anti-slip band or strip lining the garment of Figs. 11 and 12;

Fig. 14 is a vertical section taken on lines 14-14 of Fig. 13; and

Figs. 15, 16 and 17 are plan views illustrating various modifications of the band shown in Fig. 13.

In the following description certain specific terms are used for convenience in referring to the various details of the invention. These terms,

however, are to be interpreted as broadly as the state of the art will permit.

The form fitting combination garment shown in Fig. 1 comprises a lower corset portion 1 adapted to encircle the body of the wearer from the waist downwardly to a point below the hips and a connected upper portion 2 of any suitable construction having bust pockets 3 with or without the conventional shoulder straps.

The corset portion 1 of the garment of Fig. 1 comprising an inelastic front panel 4 and side panels 5 composed in this instance of one-way stretch elastic fabric which stretches only in a horizontal direction to fit the garment snugly upon the body of the wearer. The back of the garment may be of any suitable construction, for example, it may comprise a single inelastic panel extending from top to bottom of the garment as herein-after described in connection with Fig. 2.

The inelastic front panel 4 contains a plurality of spaced vertical busks or stays 6 which extend downwardly from the waistline to a point somewhat above the bottom of the garment. The lower edge of corset 1 is cut out to provide inverted V-shaped notches 7 at suitable spaced intervals to insure freedom of movement to the wearer.

Disposed about the lower edge of the garment of Fig. 1 is an interior band or lining which forms an important feature of the invention and will now be described. The said band comprises a tape-like strip 8 of horizontally stretchable elastic fabric having peaked gusset portions 9 spaced like the cut-out gores 7 in the lower edge of the corset, and a facing of sponge rubber 10 which is bonded by a suitable adhesive to one face of the strip 8 except in the areas which correspond with the inverted V-shaped notches 7. The composite band is stitched to the lower inner edge of the garment and to the sloping sides of the notches 7 so that, when the garment is viewed from the outside as in Fig. 1, the horizontally stretchable elastic strip 8 forms a visible narrow border about the bottom of the garment and fills the notches 7; and, when the garment is viewed from the inside which lies against the body of the wearer, the bottom edge consists of strips of sponge rubber separated from each other by the gusset portions 9 of the elastic strip 8, as will be evident from Fig. 3. In the embodiment of Fig. 1, furthermore, a second continuous composite band 12 is stitched about the interior of the garment just above the peaks of the gusset portions 9 of elastic strip 8, this band 12 likewise consisting of a narrow strip of horizontally stretchable elastic fabric to the exposed face of which is bonded a strip of sponge rubber.

The garters 13, of any desired number, are secured as by stitching to the composite band which forms the lower edge of the garment as previously described, and these garters are attached to the upper edges of the stockings 14 in the usual manner. When the garment is in wear, the porous cellular strips of sponge rubber described above are cushioned against the body of the wearer and exert a gentle but nevertheless tenacious traction which prevents the garment from riding up in whatever normal position the figure may assume. As a result, the tension which the garters exert on the stockings is always substantially constant and never increases to the point where it can cause undue strain.

The garment shown in rear view in Fig. 2 is generally similar to that of Fig. 1 and has an inelastic rear panel 15 stitched to the horizontally stretchable side panels 5. The panel 15 has an

upper vertical opening controlled by a slide fastener 16, and a central elastic gusset 17 at the bottom. A plurality of composite strips or pads 18 of elastic fabric-backed sponge rubber (here shown to be two in number) are inserted by stitching in the lower end of the garment, and the garters 13 are stitched to said pads 18 as shown in Fig. 2. The sponge rubber grips the body in the manner previously described and prevents the garment from riding up on the figure or exerting undue strain on the stockings.

Figs. 4 and 5 show a form fitting girdle 19 of all-elastic knitted or woven fabric having inverted triangular notches 20 cut at spaced intervals in the lower front edge. The composite anti-slip band which is stitched to the lower front edge of this garment (Fig. 4) is shown in detail in Fig. 6 and comprises a strip 21 of horizontally stretchable elastic fabric having raised triangular gusset portions 22 on its upper edge slightly larger than the triangular notches 20 and spaced to correspond with said notches, and this strip 21 is backed by a similarly shaped strip 23 of sponge rubber which may contain spaced holes 24 to provide added traction as well as ventilation. This composite strip is stitched to the lower inside edge of the garment with the sponge rubber surface inside, as indicated in Fig. 4. A similar strip without the triangular peaked portions 22-23 is stitched to the lower rear edge of the garment as shown in Fig. 5. In addition thereto, two vertically spaced linear strips 25 of sponge rubber-backed elastic tape are stitched inside the garment a short distance above the bottom edge. These strips 25 extend from a point just forward of the sides of the garment, around the sides, and partway around the back. The garters 13 are stitched to the composite strip 21-23 on the lower edge of the garment. The sponge rubber layers of the strips grip the skin of the wearer and prevent the garment from slipping as previously described.

The girdle shown in Fig. 7 comprises a body portion 27 composed of any suitable elastic or inelastic material, or a combination of elastic and inelastic panels, and has three parallel anti-slip bands arranged as follows: a composite band 28 extending around the bottom edge of the garment, a second shorter horizontal band 29 spaced a short distance above the band 28 and extending substantially across the front portion of the garment, and a third still shorter band 30 spaced a short distance above the band 29. These bands are all stitched to the inside of the garment with the sponge rubber surface of each band facing inwardly for engagement with the body of the wearer. The garters 13 are stitched to the lowermost band 28 as illustrated. The front portion of garment 27 contains a plurality of spaced vertical busks or stays 31 which extend downwardly from the upper edge of the garment to the composite band 30 which overlies the lower ends of said busks and prevents them from digging into the body of the wearer. At the upper marginal edge of the garment small pads or patches 32 of my composite anti-slip material are stitched inside the garment to cover the upper ends of busks 31, the sponge rubber facings of these pads 32 not only cushioning the ends of the busks from the wearer's body but also affording added traction which assists in maintaining the garment in the proper position on the figure. The garment of Fig. 7 may also have additional short busks 34 extending downward-

ly a short distance from the upper edge to increase the flattening effect and prevent the upper edge of the garment from curling or turning over. The upper ends of these short busks 34 are cushioned by small pads 32 similar to those previously described, and the lower ends of said busks 34 are cushioned by horizontal bands 35 of suitable length which perform the same functions as the band 30.

Fig. 8 shows a garter belt 36 having front and back depending tapes 37 of conventional design. The upper edge of belt 36 is lined interiorly with a composite linear band 38 similar in construction to the anti-slip bands described above. The internal sponge rubber facing of band 38 clings to the body at the waistline and effectively prevents slipping of the top of the garment. At the bottom of the garment I provide a continuous band 39 which is adapted to encircle the body of the wearer below the hips and is secured only to the depending tapes 37; and preferably this band 39 comprises a strip of horizontally stretchable elastic fabric backed with sponge rubber, except in the areas which are stitched to the depending tapes 37 in which limited areas the band 39 consists of inelastic fabric inserts 40 providing intermittent air spaces about the body. The garters 13 are secured to these inelastic inserts 40. When in wear, the sponge rubber surfaces of bands 38 and 39 grip the body and hold the garment in the proper position on the figure. Since the garment does not ride up on the figure, the garters 13 will never exert undue strain on the hose.

Figs. 9 and 10 are front and rear views of a pantie girdle 41 which may be composed of any suitable fabric such as woven or knitted elastic fabric. This garment is lined on the inside with a horizontal band 42 which extends circumferentially thereof just above the crotch, and with pairs of spaced parallel bands 43 which extend about the sides of the garment in position to overlie the outer thighs. The bands 42 and 43 comprise linear strips of horizontally stretchable elastic fabric having a facing of sponge rubber which grips the body as previously described. The upper edge of the garment, both front and back, contains short vertical stays 44 which are stitched in individual retaining pockets and prevent the top of the garment from curling over. As shown in Fig. 10, the upper rear edge of the garment is lined with a band 45 of composite anti-slip construction similar to the bands 42 and 43, which not only holds the garment against slipping but also cushions the upper ends of the stays 44. The band 45 may also line the front of the garment if desired, or the pockets containing the stays 44 may be formed of the same material as the band 45.

The girdle 47 shown in Figs. 11 and 12 may be composed of any suitable elastic or inelastic fab-

ric. The lower portion of this garment is lined with a circular band which is shown in detail in Figs. 13 and 14 and comprises a strip of horizontally stretchable elastic fabric 48 upon one face of which are bonded, adhesively or otherwise, spaced diagonal strips 49 of sponge rubber which may contain holes 50 for added traction and ventilation. The elastic fabric strip 48 is stitched inside the lower portion of the garment 47 as shown in Figs. 11 and 12, with the sponge rubber strips 49 facing inwardly to engage the body of the wearer for the purpose previously described.

Fig. 15 shows a modification in which the elastic fabric 48 contains a facing composed of a multiplicity of rectangular patches 51 of sponge rubber with circular holes 52; while in Fig. 16 the sponge rubber patches 53 are of various regular and irregular shapes and sizes; and in Fig. 17 I employ spaced parallel sponge rubber pads 54 of rectangular contour.

Although certain specific embodiments have been shown and described herein for purposes of illustration, it will be evident to those skilled in the art that the invention is capable of various modifications and adaptations within the scope of the appended claims.

What is claimed is:

1. An undergarment for women comprising front and back fabric panels and side panels adapted to encircle the waist and hips of the wearer, at least one of said panels including a horizontally stretchable pervious elastic member connected at its ends to adjacent panels to exert a pull to make the garment grip the body, and a layer of sponge rubber adhesively secured to the inside of one of said side panels at the bottom of the garment in position to contact the skin of the wearer for cushioning the pull of said elastic member and to grip the body to prevent slippage of the garment.

2. A garment, as set forth in claim 1, in which said sponge rubber layer is provided with holes disposed over the surface thereof and extending entirely therethrough to provide ventilation.

ESTHER CADOUS.
